JOHN M. COOKE, OF REVERE, MASSACHUSETTS, ASSIGNOR TO NICHOLAS W. MATHEY

MACHINE FOR APPLYING ADHESIVE TAPE TO FABRICS

Application filed April 1, 1927. Serial No. 180,169.

This invention relates to the work of applying adhesive tape to leather or other fabrics, either for the purpose of reinforcing the edge portions of the fabric by means of the 5 adherent tape, or to cover the edge portions of two pieces of leather or fabric which are seamed together by a row of stitches as, for example, the two sides of the upper or top of a leather boot to form a finish over the 10 back seam, both for appearance sake and to avoid roughness of the upper where it may rub against the back line of the heel portion of the foot. The present machine provides a convenient and very efficient means for rapidly 15 applying the adhesively coated tape to such a seamed fabric or to the edge portions of a thin piece of leather requiring reinforcement.

To this end the invention, generally speaking, embraces a combination of a work-supporting and work-feeding means with a reciprocatory hammer or beater arranged to press together the adhesive tape and the fabric against the work-support, in order to 20 secure the tape to the fabric. Suitable positioning guides or gages are provided for properly presenting the work to the tape-applying means, and means are also provided for softening the adhesive material on the 25 tape to render it tacky or sticky in order to facilitate the rapid action of the machine. As the tape is adhesively coated on one side there is a tendency for it to stick when wound 30 on a spool, and special means are provided for freeing or releasing the tape from such adhesive contact with the supply package 35 from which it is carried to position for application to the work.

These and other features of the invention 40 will be described in detail in the following specification and will be defined in the claims hereto annexed.

In the accompanying drawings I have illustrated 45 a simple and convenient construction and arrangement embodying the principles of this invention, and in this specific case utilizing in part a sewing machine head of well known form for the support of the working parts, in which drawings:

Figure 1 is a front elevation of the machine as a whole.

Figures 2 and 3 are detail views in elevation and plan, respectively, of the tape-freeing member.

Figure 4 is an end elevation showing, on an enlarged scale, the tape-applying and holding mechanism. 55

Figure 5 is a view on a similar scale of some of the parts shown in Figure 4. 60

Figure 6 is an end elevation of the lower part of the mechanism similar to that shown in Figure 4, showing a modified arrangement of work-guide.

Figure 7 is a detail view of the parts shown in Figure 6 taken at right angles to the plane of Figure 6. 65

Figure 8 is a detail view of the work-support in association with a modified form of tape-guiding means. 70

Figure 9 is a front elevation of the tape-guiding means shown in Figure 8.

Figure 10 is a partial plan view thereof.

Figure 11 is an end elevation showing the tape-feeding and heating means by which 75 the tape is stripped from the spool and heated on its way to the work-support.

Figure 12 is a perspective view showing two pieces of leather seamed together with the tape applied to and covering the same 80 on the inner side.

Figures 13 and 14 are detail views in plan and vertical section, respectively, showing a universal type of tape-feeding member adapted for both wide and narrow tapes. 85

For convenience I have utilized, as the main frame or head of the machine, a well-known type of sewing machine head 1, having an overhanging hollow arm 2 and a hollow base portion 3 provided with a casing 11, underneath the working parts for containing the underneath feed of the well-known fore-motion type used in sewing machines, such casing being surmounted by a plate 10 forming a work-support through which, at two 90 points, the corrugated work-feeding dogs 9 project when in action.

The main shaft 4 of the machine passes through the upper overhanging arm 2 of the head, and is provided with upper bearing lug 100

2^a and lower bearing lug 2^b for the support of vertically reciprocating parts presently to be described.

There is no need of describing the underneath feed mechanism since that is a well-known type of sewing machine feed, and it will suffice to state that the feed-dog 9 is actuated by a rotary shaft 6 formed with double cranks connected by links 5, with corresponding links on the shaft 4 to impart rotary motion thereto, and by a spindle rock-shaft 8 to which an oscillatory movement is imparted by the connecting link 7, attached to a rocker arm 8^a on the rock-shaft 8. It will, of course, be understood that any suitable mechanism may be employed for actuating the underneath feed-dog in the work-support. The entire machine is mounted on a horizontal work-table A of suitable construction carrying the parts.

In the main illustrations the machine is shown set up for use in covering the back seam of two stitched together pieces of shoe upper, such as is illustrated in Figure 12, the stitched together pieces of the upper being shown at *a*, with the adhesive tape applied to cover the inner side of the seam to avoid roughness and also give a finished appearance to the interior of the shoe at this point.

As will be later pointed out, the machine may also be used for applying adhesive tape to the edge portions of thin pieces of leather or other fabric which it is desired to reinforce.

The machine employs, in conjunction with suitable holding-down presser feet or members, a tape-pressing or applying hammer or beater by which successive portions of the work, as it is fed through the machine by correlated feeding mechanism, are pressed together so that the tape forms an adhesive contact with the leather or other fabric to which it is applied.

I will first describe the machine for pressing the fabric and the adhesive tape together into intimate contact and for feeding work intermittently, and will then describe the feeding and heating means by which the tape is carried to the work step by step with its adhesive in a softened state to facilitate quick adhesion to the fabric.

Referring particularly first to Figures 4 and 5, I provide a vertical reciprocating plunger 15, slidably mounted in bearing portions 2^a and 2^b of the head, and to its lower end is detachably secured, by the set screw 16^b, an arm 16 carrying, at its lower end, a block 16^a of leather or raw-hide to form a somewhat yielding face for what may be termed the "hammer" element of the machine. This reciprocating hammer may be actuated in any suitable manner and, as shown in the drawings, there is secured to the bar 15, a laterally projecting pin 14 carried by a clamping block 14^a, which is fastened in place by the clamping screws 14^b. The eccentric 12

on the drive-shaft 4 is operatively connected with the reciprocating and hammer bar 15, by means of the connecting rod 13, whose upper end surrounds the eccentric.

To cooperate with the four-motion feed-dog 9, which projects up through openings in the work-supporting plate 10, and moves backward in the well-known manner to impart an intermittent feed to the work resting upon the work-support, I provide two co-acting presser feet 32 and 35 one of which, in this case presser foot 32, presses the work against the underneath feed-dog 9 and is free to swing rearwardly with the work as the underneath feed dog moves toward the rear, while the other presser foot 35, during this feeding operation, is slightly raised from the work but descends upon it as the feeding movement ceases in order to pinch or hold it against displacement on the work-support, while the feeding presser-foot 32 moves forward in raised position to again engage the work and pinch it against the underneath feed-dog in order to repeat the feeding operation.

The mechanism by which this alternating pressing of the work against the feed-dog and holding of the work against the work-plate is accomplished will now be described.

A slide-bar 19, mounted rearwardly of the reciprocating hammer-bar 15, is free to move up and down in the bearing bosses 2^a and 2^b. Intermediate of these two bearings it is provided with a thrust block 20 clamped thereto by screws and having a rearward extension 20^a in which is inserted a fulcral pin 21, on which is pivoted an angle-lever 22 which has pivotal connection with the connecting link 23 with an eccentric crank pin 24 on the drive-shaft 4 so that, as the shaft 4 rotates, the angle lever will be rocked to and fro on its fulcrum.

The horizontal arm 22^a of this angle-lever carries, at its forward end, a connecting pin 25 to which is pivotally connected a vertically depending bar 30. To the lower end of this bar 30 is adjustably attached, by means of screw 32^c, a horizontal presser foot 32, whose shank 32^b extends upward to overlap the lower end of its supporting and actuating bar 30 so as to permit adjustable attachment of the presser-foot to its supporting bar. It is the function of this bar to support the presser-foot 32 so as to allow the presser foot to swing rearwardly upon the fulcral-pin 25 in order to move with the rearwardly fed work, while maintaining pressing contact therewith.

The supporting-bar 30 swings inside an overlapping guide-arm 31^b which acts to limit the forward swinging movement of the bar 30. The rearward movement, induced by the movement of the underneath feed-dog 9 on the work, serves to compress the lever spring 31 against a stop 31^a which limits the rearward movement of the presser-foot bar.

- As the presser-foot bar swings toward the rear, against the yielding resistance of its return spring 31, it cooperates with the underneath dog by its downward pressure to aid in feeding the work one step toward the rear. 5
- The actuating mechanism is so co-ordinated that as soon as it finishes its rearward stroke the swinging presser-foot bar 30 is lifted through its connection with the arm 22^a of the angle-lever 22, thereby allowing the spring to return it to forward position, while, upon such release and return, the work holding presser-foot 35, is forced down upon the work to pinch it against the work-supporting plate 10 until the presser-foot 32 again presses the work at a new point against the underneath feed-dog. This alternating lifting and pressing action of these two presser feet is effected by reason of the fact that the bar 19 is normally pressed downward by the compression spring 38 thrusting against the block 20 clamped thereon, and the fact that the fulcral point of the angle lever 22, which acts as a presser-foot actuating member, shifts alternately from pin 21 to pin 25, as will now be explained. 15
- The work-holding presser-bar 19 is normally pressed down by the spring 38 until it is stopped by its thrust against the fixed work-supporting plate. As this bar can descend no farther the fulcral pin 21, secured to and carried by it, acts as a fixed fulcrum on which the angle lever 22 is rocked by the connecting link 23, so that the forward end of the arm 22^a, of this lever, must move downwardly under the pull of the connecting link 23 to force the feeding presser-foot 32 against the work, this action occurring obviously during the forward or return movement of the work-feeding presser-foot 32. 20
- Just as soon, however, as the presser-foot 32 comes to rest against the work interposed between it and the work-supporting plate the pin 25 becomes then a fixed fulcral point and the further movement of the connecting link 23, induced by the rotating shaft, acts to swing the angle lever 22 upward about a pivotal center 25 against the resistance of the spring 38. 25
- There are two points at which both the presser-foot and the holding-foot are down on the work, namely, when the crank pin 24 is at the top of its stroke intermediate of its extreme forward and rear positions, and also when it is at the bottom of its stroke or travel. 30
- During the first quarter of its travel toward its forward position the pin 24 acts to swing the angle-arm 22 on the pin 25 as a fulcrum, thus lifting the holder 35 from the work. 35
- During the second quarter of its revolution, that is, toward its lowermost position, the holder goes down upon the work. During the first quarter when the holder is lifting and during the second quarter of the circle, 40
- when the holder is going down toward the work, the plunger 15, carrying the hammer, is going down to press or hammer down the work. During the third quarter the pin 21 becomes the fulcral point since the holder 35 is pressing on the work at the beginning of that quarter turn and, consequently, the presser-foot 32 is being lifted and the hammer also is being raised from the work. During the fourth quarter turn the hammer continues to lift while the presser-foot 32 goes down toward the work. Furthermore, during the first quarter turn, as the holder lifts, the feeding presser foot moves rearwardly by reason of the rearward movement of the underneath feed-dog to feed the work, but during the third quarter turn the feeding presser-foot, as it is lifting from the work, is free to return to forward position under the action of its return spring 31. The block of leather, constituting the case of the hammer or tape-pressing appliance, has sufficient compressibility to yield under the downward pressure of its supporting and actuating bar so that the hammer actually remains in pressing contact with the work through a substantial arc of the revolution of the cam 24 as its high part approaches and recedes from the lowermost point of its travel. It will, therefore, be seen that there is perfect correlation of the overhead feed presser with the underneath feed-dog and that all the parts are so co-ordinated that each overhead presser foot engages the work before the other is actually lifted from it. 45
- I will now describe the tape-feeding and heating means. 50
- Some distance to the rear of the machine are located two uprights or standards 50, provided, at their upper ends, with bearings to receive a horizontal shaft 51 upon which a tape-supply spool 52 is loosely mounted so as to permit the spool to slide axially in either direction in order to maintain the portion of the tape being delivered from the spool in line with the tape-guiding and drawing-off means. 55
- At a short distance below the shaft 51 is mounted a transverse rod 53, formed with a guide-loop 53^a, at its middle portion opposite the tape-applying mechanism, above described. 60
- The tape-drawing off or releasing member comprises a vertical arm 54, formed with a laterally extended slotted head 54^a. This arm 54 is secured to a supporting block or plate 54^b, whose lower end is notched or forked to straddle a fixed cross-bar 56, as shown at 54^c, Figure 11. Above the notch there is bored a central orifice in the head 54^a, into which fits an eccentric 55^a which is secured to a shaft 55, parallel with and slightly above the cross-rod 56. This shaft 55 carries a pulley 57 which is operatively connected for driving purposes with the pulley 4^b on shaft 4 in the machine head by means of a 65

crossed pulley 58. The loop 53^a does not extend forwardly beyond the foremost point of the barrel of the spool, which is indicated in dotted lines in Figure 11, so that the tape *x*, when drawn through the guide and through the drawing-off arm, will always remain in contact with the loop 53^a, which acts in part as a tensioning device as well as a guide. Obviously, the rotation of the shaft 55 and its eccentric 55^a, will cause both a vibrating or rocking movement and a lifting movement of the draw-off member 54, 54^a, which is found to be very effective in drawing off a sufficient supply of tape to feed forward, through the work-feeding devices of the machine at each cycle of operations.

Beneath the table A is mounted a heating chamber or casing 60, in which is located an electrically heated element or plate 61, through which electric current is supplied through the terminal 61^a. The tape passes down through an opening in the table around the guide-roller 62 and 63, and up through the vertical arm 60^a of the casing 60, whose upper end is provided with a guide-rod or railway 65, adjacent to the work-supporting plate 10, over which the tape is fed with its adhesively coated surface uppermost, such adhesive coating being softened to render it sticky and quickly adhesive in order that it will adhere firmly to the underside of the superimposed fabric which is fed with the tape rearwardly over the work table by the feed devices, already described.

Various types of gages or guides may be applied to the work-plate immediately in advance of the work-supporting surface thereof. In Figures 6 and 7 is shown a sheet-metal guide 42, whose tape-engaging end is bent to form a hollow loop for the passage of the tape, and which is adjustably secured in place by an attaching screw 42^a passing through a longitudinal slot in the tape-guide or gage.

To accurately position the work during its passage through the machine, appropriate work-guiding means or gages are provided which may be made in several ways according to the nature of the work and the preference of the operator.

In Figures 4 and 5 the elongated presser-foot 32 is shown provided with a medial thin fin or rib 32^a somewhat similar to a boat keel, which engages the crease or groove formed by stitching the two pieces of fabric *a*, *a*, together, as shown in Figure 12 so that, as the work is fed through, perfect alignment between the tape and the fabric to which it is applied is maintained. This gage, however, as shown in Figures 6 and 7, may be made quite separate from the presser-foot and, in that case, the gage 40, with its depending rib or blade 40^a, is supported at the lower end of a vertical bar 40^b, which slides in upper and lower bearing arms of the frame 41 and is

yieldingly pressed downward by the thrust spring 40^c, working against a thrust collar 40^d, adjustably secured to the rod 40^b. To raise the work-guide from the work a short thumb-lever 42 is pivoted on the frame 41 in position so that its short end will engage and lift a collar 40^e, adjustably secured on the upper end of the guide-carrying bar 40^b.

As before stated, the machine is intended equally for use in applying adhesive tape, or so-called friction tape, to the edge portions of a plain piece of leather without any seam. In such case the gage would be of different form from the ribbed gage or guide just described, and would need to bear against one edge of the work.

As shown in Figure 9, this gage 66 is mounted on a slidably adjustable carriage 67, arranged on the inner side of the machine and by its adjustment longitudinally of the machine head it can be said to form a lateral guide to be engaged by the edge of the work being treated.

In Figures 8, 9 and 10 I have shown also a modified form of tape-guide comprising upper and lower plates 70 and 71, having registering slots transversely of the tape which is passed through these slots 70^a and 71^a. Clamping screws 72, passing through slots in the shank portion of these gage-plates, make it possible to adjust either one of them so as to carry the width of the slot, formed by the two combined, to whatever width of tape is being used.

The particular features of the work-guiding gage shown in Figure 9 are not further described in this application since they are not herein claimed.

While in the drawings I have shown the feeding presser-foot 32 secured to the swinging reciprocating bar 30, and the holding-down presser foot 35 secured to the right line reciprocating bar 19, yet it might be advantageous, in some cases, to change these about so that the small presser foot 35 would become the feeding presser-foot and the larger presser-foot 32 would become the holding presser-foot, in order that when functioning or applying tape at the flat edge portion of a piece of leather the work could be turned around a very sharp corner.

The type of tape-unwinding or drawing-off device shown in Figures 2 and 3, while serving satisfactorily for narrow tape, is subject to the folding or doubling of the tape when used on wide tapes. If, however, the tape-guiding slot in the drawing-off device is angularly adjustable under the tension of the tape, the trouble will be overcome. Such a construction is shown in Figures 13 and 14, the characteristic feature of which is that the slotted tape-receiving member is rotatably mounted to change the angular disposition of the slot according to the direction from which the tape approaches, whether from one side

or the other, or from a position directly in line with the plane of oscillation of the arm 54. This, which is the preferred form, has an annular head 54^c at the top of arm 54 and in this head or bearing ring is rotatably mounted a flanged disk or button 54^a, having a tape-receiving slot. The slotted tape-guide is kept in place by a bottom-retaining plate 54^b, forming, in conjunction with the flange of the disk, a peripheral groove or track receiving the bearing ring 54^c.

It will be observed that the vibratory stripper does not grip the tape between two jaws and, therefore there is no adhesion of the tape to the stripper device. Furthermore, as the inside or adhesively coated face of the tape, as it is drawn off from the spool, reaches the work table lies uppermost the fabric to be reinforced is superimposed upon said upper turned coated face and pressed down against it by the presser and feeding members. This arrangement prevents adhesion of the tape to the beater pressing member or hammer and also allows the fin of the overhead guide 25 to ride in the seam-crease which it could not do if the adhesive tape were uppermost. Furthermore, the guide members, which guide the tape through the heater to the work support, engage the back or uncoated surface 30 of the tape so that the adhesive is not removed by frictional engagement with the guides.

What I claim is:

1. In a machine for applying adhesive tape to fabric, the combination with a work-support, of intermittently acting work-feeding means and a reciprocating hammer arranged to press successive portions of a tape and of the fabric together in the intervals between successive feeding movements of the work.

2. In a machine for applying adhesive tape to fabric, the combination with a work-support, intermittently acting cooperative feeding mechanism arranged partly above and partly below the work, an overhead reciprocating plunger provided with a pressing member of yielding material, said plunger being actuated to press the interposed tape and fabric against the work-support in the intervals between the feeding movement of the work.

3. In a machine for applying adhesive tape to fabric, the combination with a work-support, of intermittently acting work-feeding means, an intermittently acting work-holding presser coordinated with the work-feeding means to act in alternation therewith, and a reciprocating hammer arranged to press interposed contacting layers of fabric and adhesive tape against the work-support when the work-holding presser is in active position.

4. In a machine for applying adhesive tape to fabric, the combination with means for alternately feeding and pressing together a

piece of fabric and an adhesive tape, a revolvable tape-carrier, means for heating the tape before it is pressed against the fabric, and means for intermittently stripping predetermined lengths of the tape from the tape-carrier in coordination with the feeding means.

5. In a machine for applying adhesive tape to fabric, the combination with a carrier-spool upon which the adhesive is wound, of tape-guiding means, of a vibratory tape-engaging and stripping means for drawing off a predetermined length of tape from the spool, said spool being mounted to be revolved by the pull of the tape and to be shifted axially to maintain the unwinding tape in line with the tape-guiding means.

6. Means for delivering to tape-applying mechanism predetermined lengths of adhesive tape wound on a carrier-spool embracing in combination means for supporting a revolvable tape-carrying spool to permit axial movement of the spool, a stationary guiding means for receiving the tape unwinding from the spool, a vibratory stripper through which the tape passes on its way to the tape-applying mechanism, and means embracing a rotary shaft and a stationary shaft having operative connection with the vibratory stripper to cause it to draw off from the spool predetermined lengths of the tape.

7. In combination with a revolvably mounted spool on which is wound adhesive tape, a vibratory stripper arm through which the tape unwinding from the spool is passed, a rotary shaft carrying an eccentric cam engaging said stripper arm, said stripper arm being also slotted at a distance from the cam for engagement with a stationary member whereby the stripper arm is caused to vibrate and thereby draw off from the spool predetermined lengths of tape.

8. In a machine for applying adhesive tape to fabric, the combination with a work-support, means for alternately feeding and pressing superimposed layers of adhesive tape and fabric in unison, tape-guiding means associated with the work-support and embracing two slotted adjustable plates mounted one above the other with registering slots whose conjoint effective length may be varied for different widths of tape by the lateral adjustment of one plate in relation to the other.

9. A tape-guiding gage for guiding the tape to tape-feeding and applying mechanism, comprising two guide plates adjustably secured in position each having a pair of aligned slots through which the tape is drawn, the slots of each plate being arranged to be set in registered relation both to narrow the effective width of the slots to fit different widths of tape and to position any width of tape to proper relation to the tape-applying mechanism.

10. In a tape-applying machine, the com-

bination with a rotatable tape-carrying spool, of a vibratory tape-stripping device having a self-adjusting slotted tape-receiving member rotatably mounted therein.

5 11. In a machine for applying adhesive tape to fabric the combination with means for supporting adhesive tape and superimposed fabric, of intermittently acting work-feeding work-holding means for advancing and holding the tape and the superimposed fabric together, means for heating said tape to soften its adhesive coating and guiding means for guiding the tape with its adhesive side uppermost into contact with the 10 underside of the superimposed fabric, and work-hammering means arranged above the fabric to cause the fabric to adhesively unite with the underlying portion of the tape.

12. In a machine for applying adhesive tape 20 to fabric the combination of means for intermittently stripping predetermined lengths of tape from a spool on which the tape is coiled, a tape heating conduit, tape guiding means arranged to engage the uncoated face of the 25 tape, and guide it through said conduit to the work support with its adhesive face uppermost, and means for pressing down on said tape a superimposed piece of fabric to be reinforced, and means for intermittently 30 feeding the adherent tape and fabric over the work support.

13. In a machine for applying adhesive tape to fabric, the combination with a work support, of alternately acting work-feeding 35 and work-holding means, a reciprocatory hammer arranged to hammer the tape and the fabric against the work support in advance of the work-holding means.

In witness whereof, I have subscribed the 40 above specification.

JOHN M. COOKE.
